UNITED STATES PATENT OFFICE.

SETH W. HERRICK, OF WASHINGTON, N. J., AND PHILLIP J. LAWRENCE, OF EASTON, PA.; SAID HERRICK ASSIGNOR TO SAID LAWRENCE.

PEDAL FOR ORGANS.

SPECIFICATION forming part of Letters Patent No. 323,678, dated August 4, 1885.

Application filed October 24, 1884. (No model.)

To all whom it may concern:

Be it known that we, SETH W. HERRICK, of Washington, in the county of Warren and State of New Jersey, and PHILLIP J. LAWRENCE, of Easton, in the county of Northampton and State of Pennsylvania, have invented certain new and useful Improvements in Pedals for Organs, of which the following is such a full, clear, concise, and exact description as will enable others skilled in the art to which our invention appertains to make and use the same, reference being had to the accompanying drawings, forming part of this specification.

The use of pedals for organs as they have heretofore been constructed has been attended with certain difficulties—as, for instance, the great amount of exertion required to operate them, the fact that the greatest power has been when least needed, as there was more contact of the feet with such pedals at the outset of the tread than when they approached their downward limit, but required further pressure in order to exhaust the bellows, in which case the extra pressure could only be given by the toes of the operator, which not infrequently pushed against the bellows-straps, thus causing them to wear out. They have also caused a cramping of the feet and legs, particularly of tall persons. And aside from these objections such pedals have taken up considerable room inside of the case of the organ, a portion of which had to be cut away in order to permit of their being operated; and inasmuch as the bellows-straps were drawn inward and more around the pulleys as the pedals were pressed down, this made the operation of exhausting the bellows more difficult just at the time when the greatest power was needed and when the pressure could only be given by the toes of the operator; moreover, the cutting away of the front portion of the case of the organ in order to make room for the pedals has made it impracticable to give to an organ the same appearance and neatness of finish that are given to a piano.

The object of our invention is to overcome these difficulties, and to construct pedals in such a manner as to permit of a free and easy movement of the feet and legs, while also giving an even distribution of power throughout

the entire tread; and it consists, first, in constructing a pedal having two arms, one being placed inside of the case and connected with the bellows-strap, which arm projects in the direction of the length of the organ for a sufficient distance to give a good leverage, while the other, after passing through a hole or opening in the organ-case, projects outwardly, assumes practically the same direction as the inside arm and forms the foot-lever; second, in setting or securing such pedal or pair of pedals in a slightly-inclined position, so that the motion of the foot-lever, instead of being directly up and down, is also inward toward the organ as it is pressed down by the feet, thus giving an easier movement to the feet and legs of the operator; and, third, in making an adjustable connection of the arm inside of the case with the bellows-strap, whereby such strap is made to retain its perpendicular, or the same relative position on the pulley, no matter what position may be given to such connecting-arm by the tread of the pedal.

In the drawings, Figure 1 is a perspective front view of a pair of organ-pedals, showing how they may be attached or secured in place, and also their connection with the bellows-straps, a portion of which, together with the pulleys over which they extend, also appear. Fig. 2 is a rear view of a pair of such organ-pedals, showing more clearly the ends of the bellows-straps and their connection with the pedals; and Fig. 3 is a view of one of the pedals detached from the organ, and parts in connection with which it is intended to be used, while Fig. 4 is a side view of one of the pedals set at an incline produced by having the support B, a portion of which is shown, made thicker at one end than the other, or by being set on an inclined base, a section of which appears in this figure.

In these drawings, A represents the foot-lever or outwardly-projecting arm of the pedals, and a the arm which goes inside of the case of the organ. B represents a support, to which the pedals may be hinged or otherwise secured, and b studs whereby the hinging or securing of the pedals to the support B may be effected. C C represent the bellows-straps, and c c the ends of the same, which are con-

nected to the arms *a a*, of the respective ped-
als; and D D represent the pulleys over which
the bellows-straps pass.

In practice a right and left hand pedal may
5 be cast from a pattern, with arms A *a* project-
ing from each, as shown, or similarly thereto,
for a sufficient distance to give a good lever-
age from that part of the same where they are
hinged or secured. After the necessary holes
10 are drilled or otherwise formed in them, and
are finished, as desired, the outer projecting
arm, A, may be made to pass through a suit-
able opening or hole in the proper part of the
front portion of the organ-case, thus bringing
15 such arm, which forms the foot-lever outside
of the case of the organ, while the other arm,
a, remains inside of the same and projects or
extends toward the ends of the organ, pref-
erably parallel with the case. That portion
20 of the outward arm which is intended to re-
ceive the pressure of the foot assumes for a
greater or less distance a direction very much
the same as the inside arm—that is, toward
the end of the organ—but not necessarily or
25 even preferably parallel with the case of the
organ, the object of the direction given to
such extension being to allow a free and easy
movement of and at the same time natural po-
sition of the feet and legs of the operator. In
30 like manner the other pedal may be placed in
position, but assuming, of course, an opposite
direction, as its arms project toward the other
end of the organ. These pedals may then be
hinged or secured in place, as by the support
35 B; but they are preferably given an inclined
position, which may be done by having the
support B made thicker at one end than the
other, or by the adjustment or construction
40 of that portion of the respective pedals which
is secured or permanently fixed as to the sup-
port B.

The arms A A when so inclined will move
inward toward the organ as the feet of the op-
erator press down upon them. This will give
45 a natural movement of the feet, and at the
same time permit the ball of the foot to rest
upon the pedal throughout the entire tread,
and consequently there is no lost power, as
the treading does not require a forced position,
50 and the bellows can be exhausted with the
fewest strokes possible.

The inside arms, *a a*, may be pivoted or oth-
erwise adjustably secured to the bellows-straps,
the ends of which are usually tinned, so as to
55 give protection and strength to the same. By
making such adjustable connection with these
straps they will be kept in the same relative

position to the pulleys D D, over which they
extend during the movement of the arms *a a*,
the position of the straps being practically 60
perpendicular.

By having the pedals of an organ constructed
and arranged as above explained a powerful
leverage is given, so that the operation of
pumping the organ is much easier than it has 65
heretofore been, and as the feet and legs are
given a free and easy position the performer
does not become weary through exertion. It
will also be observed that the pedals take up
but little room inside of the organ, inasmuch 70
as the arms *a a* move in the direction of the
length of the organ, and not inward toward
the center of the same, as do pedals of the
construction heretofore in use. Moreover, the
organ may be made with a case resembling 75
that of an upright piano, which will, of course,
make it better in appearance, while at the
same time it will be more desirable in every
way than it has heretofore been possible to
make an organ. 80

Having thus described our invention, what
we claim as new, and desire to secure by Let-
ters Patent, is—

1. In combination with an organ, a pedal
having two arms projecting substantially in 85
the direction of the length of the organ, one
being inside of the organ-case and secured to
or connected with the exhaust-bellows strap,
the other extending outside and in front of the
case, and forming the foot-lever, substantially 90
as described.

2. In combination with an organ, a pedal
having an arm projecting inwardly, substan-
tially in the direction of the length of the or-
gan, and secured to or connected with the ex- 95
haust-bellows strap, and an outwardly-pro-
jecting arm forming the foot-lever, such pedal
being hinged or secured at an incline, whereby
the motion of the foot-lever when pressed up-
on is downward and inward toward the organ. 100

3. In combination with an organ, a pedal
having an arm extending inside of the organ-
case in the direction of the length of the or-
gan, such arm being pivoted to or adjustably
connected with the exhaust - bellows strap, 105
whereby such strap is made to retain its same
relative position during the tread of such pedal,
substantially as described.
